UNITED STATES PATENT OFFICE.

FRIEDERICH JEBENS, OF RATZEBURG, PRUSSIA, GERMANY.

FLOATING LOCK.

SPECIFICATION forming part of Letters Patent No. 423,561, dated March 18, 1890.

Application filed October 26, 1889. Serial No. 328,223. (No model.)

To all whom it may concern:

Be it known that I, FRIEDERICH JEBENS, engineer, a subject of the King of Prussia, German Emperor, and a resident of Ratzeburg, 5 in the Province of Schleswig-Holstein, Kingdom of Prussia, German Empire, have invented certain new and useful Improvements in Floating Locks, of which the following is a clear description.

10 In order to make my invention more clear, I refer to the accompanying drawings, in which similar letters denote similar parts throughout the several views.

Figure 1 is a view in perspective of my floating lock. Fig. 2 is a sectional elevation of the same. Fig. 3 is a cross-section of the lock. Fig. 4 is a cross-section of the well. Fig. 5 is a top view of the lock on its floating cylinder. Fig. 6 is a vertical section showing 20 the mechanism for closing the orifices *ff* drawn to a larger scale. Fig. 7 is a plan of the lever-arm for operating the cover. Fig. 8 is a sectional view of the orifice with the cover closed on a still larger scale.

25 This floating lock is for use in canals where the difference of water-level between the reaches is so great that an ordinary lock-chamber is not sufficient for the transport of a vessel from one reach to the other.

30 In the perspective view of the lock shown in Fig. 1, A is the lower and B the upper reach, and C is the lock-chamber, which is raised and lowered in the manner hereinafter described. At each end of the lock-chamber, as 35 also at the ends of the upper and lower reaches, are lock-gates *p'* and *p''*, which may be opened. If a vessel passes from A to B, the lock-chamber is placed on a level with the lower reach, and after the gates *p'* have been opened and 40 the ship admitted into the lock-chamber the gates will be closed again. The lock-chamber is now raised and the upper gates opened, when the ship will be let out and can proceed farther. The process is pretty much the 45 same when a vessel passes from B to A.

Referring to Figs. 2 and 3, D is a well filled with water up to line *g h*. E is an empty water-tight iron drum, the upper end of which is shown in Fig. 2 by a dotted line *a b*. F is 50 a cylinder connected with drum E, and into which the water of well D may be driven

through openings *ff*. On this cylinder, which has its upper end open, the lock-chamber C rests. The cylinder has, however, another purpose hereinafter to be described. The displacement of the drum is sufficient to hold it, the cylinder, and lock-chamber in equilibrium. In consequence these three parts remain floating. These three parts are all guided vertically up and down. As may be seen in Fig. 4, two guiding-claws *c c* are attached to the outside of drum E, which slide on guiding-rods *d*, Figs. 2 and 3, running down the sides of the well. Further, two guiding-blocks *e e*, Fig. 3, are attached to the upper part of the cylinder or under the lock-chamber, which said blocks run on guides supported in trestles *G G*.

Fig. 5 shows a plan of the cylinder with its guide-blocks *e e*. The whole, consisting of drum, cylinder, and lock-chamber, is thus guided vertically, and it only remains to remark that the vertical guides may be supported by brick-work piers instead of iron truss-work, as shown in the drawings. The openings *ff* in the cylinder may be closed, and when the drum, with its cylinder and lock-chamber, is in a state of rest they are closed. On raising the lock-chamber water flows out of the cylinder into the well through the openings *ff*, which have then been opened, while in sinking the lock the water flows in the opposite direction. The openings *ff* may be closed and opened in any convenient manner. One system of effecting this result is shown in Figs. 6, 7, and 8 drawn to a larger scale. *a b* is the cover of the drum; F, the cylinder. The standards *k'* are fixed to the cover of the drum, and in these standards the lever *G* has its bearings. The cover *P* for the opening *f* is fixed to the end of lever *G*. Lever *G* may be operated by a chain *n*. Orifice *f* is provided with an india-rubber ring, on which the cover closes. As, however, the lever and cover are tolerably heavy, it is advisable to introduce some motive power for operating the same. In the drawings hydraulic power is intended, water being pumped into the cylinder *l* underneath the piston when the cover is to be raised. A small hydraulic pump may be used for this purpose. Cylinder *l* is supported on iron guides

m m. The working of the cover may, however, be effected in any other suitable manner, as the particular mechanism connected with this arrangement is not involved in the 5 present invention.

In the upper part *ik* of the well, Figs. 2 and 3, the walls of the cylinder are thrown forward, projecting nearer to the sides of the cylinder, thus diminishing the annular space 10 between cylinder and well. It is not necessary that this space should be made water-tight, and the water-level in the well stands at the same height as in the cylinder, or the variation is only slight. If now the lock- 15 chamber is filled with sufficient water to overcome the displacement of the drum, the water-level in the annular space between well and cylinder will stand higher than that in the cylinder, (assuming the openings *ff* of 20 the cylinder to be closed,) and vice versa when the chamber contains less water than necessary to overcome displacement of drum. The annular space between well and cylinder is therefore diminished in order that the variation 25 in the height of the lock-chamber may remain slight when the same is more or less loaded with water. Toward the lower part a widening of the well, as in Figs. 2 and 3, may be introduced with advantage, as in this case 30 any giving in of the walls of the well can have no very damaging effects. In wells cut in hard rocky soils such widening is, on the contrary, not necessary.

When the lock-chamber is raised, it may be 35 brought to a standstill by closing the openings *ff* while the water-level of the chamber is somewhat below that of the upper reach. Thus more water will flow into the chamber than that necessary to balance the displacement of 40 the drum on the gates *p''* being opened, and consequently weight enough is present in the lock-chamber to overcome the displacement

of the drum and effect the earlier or later descent of the lock. On having descended, the lock will be arrested in such a position that 45 the level of the water in the same is a little above the water-level of the under reach.

In order that water may not run out at the ends of the lock-chamber when the gates *p'* or *p''* are opened, the gates of the chamber 50 are made water-tight in a particular manner, not necessary to be described here, as such is already carried out in the ascensions in les Fontinettes and la Louvière, in France and Belgium. 55

I reserve to myself the right of using two cylinders and wells in the manner of the one described—for instance, in the case of big lock-chambers.

Having thus fully described the nature of 60 my said invention, what I desire to secure by Letters Patent of the United States is—

1. A floating lock, substantially as herein described, consisting, principally, of a drum, a cylinder resting on the same, and lock-chamber resting on the cylinder, which three parts are together guided vertically and float in a well, the top of the wall of which projects inward close to the sides of the cylinder, so that no water-tight sealing of the well is necessary. 70

2. The cylinder resting upon the drum and provided with the openings at the bottom of its sides, which openings may be closed or opened, whereby the stoppage or regulation of the motion of the lock-chamber, cylinder, 75 and drum, constituting one whole piece, may be effected.

In witness whereof I have hereunto set my hand in presence of two witnesses.

FRIEDERICH JEBENS.
